UNITED STATES PATENT OFFICE.

FRED W. HAAS, OF PITTSBURGH, PENNSYLVANIA.

WATER-COOLING TOWER.

Application filed July 12, 1921, Serial No. 484,102. Renewed October 30, 1924.

To all whom it may concern:

Be it known that I, FRED W. HAAS, a citizen of the United States, residing at Pittsburgh, in the county of Allegheny and State 5 of Pennsylvania, have invented a new and useful Improvement in Water-Cooling Towers, of which the following is a specification.

My invention relates to water-cooling towers and its objects are to provide improved means for the escape of heat therefrom, for bringing air into contact with the hot water spray, and for preventing the spray or fine sheets of water from blowing out through the louvres. Other objects appear hereinafter.

Referring to the accompanying drawings, Fig. 1 is a central vertical section of a water-cooling tower containing some of the said improvements; Fig. 2, a top plan view of a portion of the tower; Fig. 3, a vertical section of Fig. 2 on the line III—III; Fig. 4, a side view of one of the spraying devices; Fig. 5, a vertical cross-section of the central portion of the upper part of the tower; and Fig. 6, a sectional fragmentary view showing a modification of my invention.

On the drawings, 1 and 2 designate respectively the upper and the next lower sections of a water-cooling tower, the lower section being shown broken away. I do not limit my invention to the use of two sections as it may contain only one section or several superposed sections. Each section has a number of sides 3 inclined inwardly and upwardly so as to form frustums of pyramids. The sides are louvres of any suitable type.

The top of section 1 is provided with a series of horizontal pans 4 arranged side by side and supported in any suitable manner, 40 as by the joists or cross-pieces 5. Adjacent cross-pieces 5 are spaced apart so as to provide open spaces 6 between adjacent pans for the escape of heat from the section 1.

A water-receiving trough 7 lies above the 45 pans 4 and transversely thereof, and is supplied with water by the pipe 8. The water from the trough flows over its sides into the pans 4. The upper edges of the trough are, directly over the pans 4, provided with depressions or notches forming teeth 9. The 50 edges of the trough directly over the spaces between the pans are not depressed or notched, and a strip 10 is laid on the said edges so as to raise their height and prevent

water flowing over the trough into the same 55 when the water supplied to the trough is temporarily increased.

In the section 2 the pans 4 need not be spaced apart. There are pendant from the bottoms of the pans 4 a number of spraying devices 11, which are downwardly tapered tubes of sheet-metal each having a spray-forming deflector 12 supported at the lower end of a wire 13 extending down through the tube and below its lower end. The hot water falling from the deflectors becomes finely divided sprays which are condensed by the air passing through the louvres, the condensed water from the pans in one section falling into the pans of the next lower 70 section.

In order to further cool the spray, I supply numerous small jets of air to the interior of the sections. The jets may be supplied from any number of supply pipes lying in any direction in the sections, but I have shown them supplied by one vertical pipe 14 extending up through the sections and provided with numerous small holes 15 from which small jets of air may flow into contact with the falling spray. Air is supplied to the pipe 14 by any suitable means, as the blower 16.

In case of strong winds blowing through the sections or if the blasts of air from the pipe 14 cause the spray to be driven out through the louvres, I may provide wire screens within the sections, inclined in the general direction of the adjacent sides and supported a few inches from the louvres. 85 On Fig. 6, I have shown only one screen 17. The screens should have a fine mesh, one-fourth inch or smaller. The spray striking the screens adheres to it and flows downwardly. By reason of the small size of the 90 mesh and the inclination of the screens, the water which passes over the open spaces of the screens is blown against the lower wires of the spaces, and continues its way downward to the next horizontal wire. If the 95 screens were vertical, the water clinging to the horizontal wires would be blown beyond the screen.

I claim—

1. In a water-cooling tower, a hollow section, a series of open-top pans supported at the top of the section and having spraying devices pendant from their bottoms, adja-

cent pans being separated by open spaces, and a water supply trough lying transversely across the pans and above the same having depressions in its edges directly over the 5 pans, the edges directly over the spaces between the pans not being depressed.

2. In a water-cooling tower, a hollow section, a series of open-top pans supported at the top of the section and having spraying 10 devices pendant from their bottoms, adjacent pans being separated by open spaces, a water supply trough lying transversely across the pans and above the same and having depressions in its edges directly over the 15 pans, the edges directly over the spaces between the pans not being depressed, and a strip covering the said edges to allow the water-level to rise in the trough tem-

porarily without overflowing into the said spaces.

3. In a water-cooling tower, a hollow section having a louvre side, a pan supported at the top of the section and having water spraying devices pendant from its bottom, and a relatively fine-mesh screen adjacent to the said side and inclined inwardly and upwardly.

4. In a liquid-cooling apparatus, a pan therein having an opening in its bottom, a concave spreader below the opening arranged to receive into its concavity the liquid from the opening and turn it into spray as it flows over the edge of the spreader.

Signed at Pittsburgh, Penna., this 8th day of July, 1921.

FRED W. HAAS.
